UNITED STATES PATENT OFFICE.

GEORG FRIEDRICH GIESECKE, OF LEIPSIC, SAXONY, GERMANY.

DESIGN FOR TYPE.

SPECIFICATION forming part of Design No. 18,751, dated November 27, 1888.

Application filed October 31, 1888. Serial No. 229,670. Term of patent 7 years.

To all whom it may concern:

Be it known that I, GEORG FRIEDRICH GIESECKE, a citizen of Germany, residing at Leipsic, Saxony, Germany, have invented and produced a new and original Design for Printing-Types; and I do declare the following to be a full, clear, and exact description of the same, reference being had to the accompanying drawing, forming a part thereof.

10 The nature of the design is clearly shown in the accompanying typographic impression, to which reference is made; and it consists of an initial letter, as shown.

15 The letters have a heavy black middle surrounded by a white border. Each letter is on a block having a surface covered with minute black dots and an ornamented border consisting of curved lines.

20 The border for the letter A consists of three curves, two meeting underneath the letter, and there are two wing-like impressions below. The third curve is at the top, its ends coming to those of the other curves. The border of the letter B consists of four curves, a shell being at the top, a rosette at each side.

25 The border of the letter C consists of two curves at the top, a curve at the bottom, carrying an escutcheon, and a reverse curve at each lower quarter. The border of the letter D consists of two curves at the top, two curves at the bottom, and two reverse curves at the top quarters.

30 The border of the letter E has two curves at the top, two at the bottom, and a reverse curve at the middle of each side. The border of the letter F is somewhat like that of the letter E, the reverse curves being smaller.

35 The border of the letter G consists of a curve at the middle of the top, a curve at each corner of the top, a reverse curve below each of these, and a curve at the bottom having scroll ends and supporting a pair of wings at the middle.

40 The border of the letter H is similar to that of the letter E, the top curve being flatter and the reverse curves higher up. The border of the letter I has the reverse curves nearly the whole length of the sides, a wing projecting outwardly from each curve.

45 The border of the letter J has the top curves reversed and somewhat flattened out, the side reverse curves being somewhat up toward the upper quarters of the block. The border of the letter K has two top curves, then a curve

55 at each side, then a reverse curve at the lower quarters, and a scroll-like curve at the bottom. The border of the letter L is somewhat like that of the letter J, the top curve not being reversed. The border of the letter M consists of two curves at the top, somewhat apart, with a shell between, a small reverse curve at each upper quarter, a large curve at each lower quarter, and a small, sharp, fluted curve at the bottom. The border of the letter N is somewhat like that of the letter M, the top curves being flattened and there being no bottom curve. The border of the letter O is somewhat like that of the letter I, the top curves being more rounded and the bottom curves being reversed. The border of the letter P is somewhat like that of the letter F, the curves being further apart at the top and bottom and the side reverse curves being smaller. The border of the letter Q is somewhat like that of the letter I, the top curves being reversed and supporting a pair of wings and the bottom curves being more rounded. The border of the letter R is substantially that of the letter N reversed. The border of the letter S is the same as that of the letter N, the side and bottom curves being rounder. The border of the letter T is somewhat like that of the letter R, the top of the block being wider in proportion to the lower. The border of the letter U is the same as that of the letter J, the top and bottom curves being flattened out. The border of the letter V consists of a pair of wings on top, a cyma-recta and a cyma-reversa curve on the sides, and a scroll curve at the bottom. The border of the letter W is substantially like that of the letter V. The border of the letter X is like that of the letter N, the side curves carrying a reticulated inward projection, and the meeting ends at the bottom supporting a pair of wings. The border of the letter Y consists of two curves at the top supporting a network from which there is a pendant, a curve at each side, and two curves at the bottom supporting a scroll-like impression. The border of the letter Z is like that of the letter W, instead of the bottom curves there being two reticulated surfaces with an ornament between. All the borders of these letters have diverse tracery lines, differing in different letters, as shown.

50 55 60 65 70 75 80 85 90 95 100

All of the letters except I and J have some-

(over)

thing projecting into the spaces about which the lines of the letters are formed. Some of them have flowers and some only a portion of the curves or scrolls of the border.

5 The leading feature of this design is an escutcheon-shaped block with an ornamented border and minute dots on its surface, and on the block is a black letter with a white border.

Having now described my invention, what I
10 claim is--

The design for a font of printing-type, as shown and described.

In testimony whereof I affix my signature in presence of two witnesses.

GEORG FRIEDRICH GIESECKE.
